REFRIGERATION APPARATUS

Charles H. MacFarland, Rocky River, Ohio, assignor to Westinghouse Electric & Manufacturing Company, East Pittsburgh, Pa., a corporation of Pennsylvania

Application September 11, 1942, Serial No. 457,907

4 Claims. (Cl. 211—143)

This invention relates to refrigerator cabinets and more especially to a shelf for such cabinet.

It is an object of the invention to provide a shelf for a refrigerator cabinet, which shelf is adapted to slide out of the way completely to make room for tall objects.

A further object of the invention is to provide a sliding shelf which occupies but little usable space in the refrigerator cabinet when slid out of the way.

These and other objects are effected by my invention as will be apparent from the following description and claims taken in accordance with the accompanying drawings, forming a part of this application, in which:

Fig. 1 is a side elevation of the lower portion of the food-storage chamber of a domestic refrigerator cabinet with portions of the side wall broken away to show the sliding shelf of this invention;

Fig. 2 is a front elevation of the portion of the refrigerator cabinet shown in Fig. 1 as seen through the door opening of the cabinet;

Fig. 3 is a plan view of the edge portion of the sliding shelf of this invention;

Fig. 4 is an elevation of the edge portion of the shelf shown in Fig. 3;

Fig. 5 is a section on the line V—V of Fig. 4 and shows also the slide rail of the shelf;

Fig. 6 is a section on the line VI—VI of Fig. 1;

Fig. 7 is a plan view of an edge portion of a modification of the sliding shelf of this invention and of a portion of the slide rail of the shelf;

Fig. 8 is an elevation of the edge portion of the shelf of Fig. 7 and of a portion of the slide rail of the shelf; and,

Fig. 9 is a section on the line IX—IX of Fig. 8.

Referring to the drawings for a description of the invention, the reference numeral 9 designates a refrigerator cabinet defining a food-storage chamber 10. The cabinet 10 has an access opening 11 in the front wall thereof and a door 12 for said access opening. The cabinet 10 may be cooled by any convenient means, such as for example a cooling unit (not shown) located in the upper portion of the food-storage chamber 10, as shown in the patent application of J. H. Ashbaugh, Serial No. 409,485, filed September 4, 1941, which became Patent #2,343,166 on February 29, 1944.

A high humidity food-storage vessel 13 is located adjacent the bottom of the food-storage chamber 10. The vessel 13 comprises a stationary glass shelf 14 and a deep pan 16 suspended therebelow. The vessel 13 is spaced from the rear and

bottom walls and from the door 12 of the cabinet 9 to provide an air-circulating path around the vessel 13 to cool the same. The convectional air currents in such a cabinet are usually downwardly along the rear wall, forwardly along the bottom, and upwardly along the door 12 of the food-storage chamber, as more particularly explained in the above-mentioned patent application of J. H. Ashbaugh.

10 The refrigerator shelf 17 of this invention is located above the glass shelf 14 and comprises an articulated grid 18 supported at its side edges 19 in channel-shaped rails 21 secured by screws 22 in the side walls of the food-storage chamber 10. In the first embodiment of my invention shown in Figs. 1 to 6, the grid 18 comprises a series of round parallel bars 23, each of which has a straight central portion 24 and two end portions 26. The end portions 26 are bent at an acute angle to the central-straight portion 24 and then looped around the extremity of the straight portion 24 of the bar 23 adjacent to the bar 23 just described. The looped end portions 26 of each bar 23 form a bearing for the straight portion 24 of the adjacent bar 23 and, in addition, provide surfaces on which the shelf slides in the rails 21.

The rear end of each rail 21 terminates a short distance from the rear wall of the cabinet 9 and the rear end 20 of the lower flange of each rail 21 is bent downwardly to provide a rounded edge on which the looped ends of the bars 23 slide downwardly when the shelf 17 is pushed back.

It will be apparent from the above description 35 that the shelf 17 is adapted to slide back and forth on the rails 21 and that, as the shelf is pushed back, the bars 23 slide off the rear edge of the rails 21 and drop progressively downwardly along the rear wall of the food-storage chamber 40 and descend into the air duct between the vessel 13 and the rear wall of the food-storage chamber 10. The air duct between the vessel 13 and the rear wall of the cabinet 9 thus also serves as a storage space for portions of the shelf 17 when the shelf is pushed back a substantial distance.

The shelf 17 may be held in any desired position on the rails 21 by means of a clamping device secured to the front edge of the shelf 17. The clamping device comprises a U-shaped channel 32 secured to the end portions 33 of the first bar 23 of the shelf 17. Two guide plates 36 are secured near the ends of the U-shaped channel 32 and two additional guide plates 37 are secured at a spaced distance from one another 55 near the central portion of the U-shaped chan-

nel 32. A clamping bar 38 passes through an adjacent pair of guide plates 36 and 37 and is journaled therein. Another and similar clamping bar 39 passes through and is journaled in the other pair of guide plates 36 and 37. The two clamping bars 38 and 39 are co-axial and their adjoining ends 41 and 42, respectively, are spaced from one another. A slot 43 is formed in the central portion of the lower wall of the U-shaped channel 32. An operating handle 44 is secured to the rod 39 adjacent to but spaced from the end 42 thereof and projects through one end of the slot 43. A similar operating handle 46 is secured in a similar manner to the end portion 41 of the rod 38 and projects through the other end of the slot 43. A compression spring 47 engages the ends 41 and 42 of the rods 38 and 39, respectively, and bears against the two operating handles 44 and 46 to bias the ends 48 and 49 of the rods 38 and 39, respectively, against the rails 21 adjacent thereto.

Thus, by forcing the two operating handles 44 and 46 together, spring 47 is compressed and the clamping action of rods 38 and 39 against the rails 21 is released so that the shelf 17 may be slid back and forth to any position along the rails 21. On releasing the operating handles 44 and 46, the spring 47 again biases the rods 38 and 39 to exert their clamping action to hold the shelf 17 in the desired position. The shelf can thus be slid back partially to provide storage space in front of the shelf for tall objects and storage space for smaller objects on the remaining horizontal portion of the shelf.

A second modification of the shelf structure is shown in Figs. 7, 8, and 9 and is designated by the reference numeral 50. In this construction the end portions 51 of a series of straight parallel rods 52 are looped to form a substantially complete circle. Tie links 53 are formed of an elongated metal plate which is provided with a hole 54 at one end thereof and a second hole 56 at the other end. The looped end portions 51 of each rod 52 pass through hole 54 of one link and hole 56 of an adjacent link respectively to form a chain structure at the edges of the shelf 50. The shelf 50 slides on the rails 21 in the same manner as described in connection with the shelf 17.

It will be apparent from the above that the shelf of this invention can be slid completely or partially toward the rear wall of a refrigerator and can be retained in any desired position. It will be further apparent that when the shelf of

this invention is slid back a substantial distance, portions thereof drop into an air duct at the rear of a vessel in the cabinet and thus occupies but little of the usable space in the food-storage chamber 10.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are specifically set forth in the appended claims.

What I claim is:

15. An articulated shelf comprising a series of metal rods, the central portion of which rods are straight and parallel to one another to provide an article-supporting structure and the end portions of which rods engage each other to form a chainlike structure to afford movement of said rods with respect to one another.
20. An articulated shelf comprising a series of rods, the central portions of which are straight and parallel to each other, and the ends of each of a plurality of said rods being bent through an angle greater than 90° with said straight portion, and then looped around the straight portion of one of the rods lying adjacent thereto.
25. A member for an articulated shelf, said member comprising a rod of substantially uniform diameter, said rod having a central straight portion and two end portions each bent through an angle greater than 90° with the straight portion and then looped into a circle, each of said 30. circles being of a size and located to form a bearing for the straight portion of a similarly shaped shelf member passing through each of said circles and lying parallel and close to the straight portion of said first-named rod.
35. A member for an articulated shelf, said member comprising a rod of substantially uniform diameter, said rod having a straight central portion and two end portions each bent through an angle greater than 90° with the straight portion and then looped into a circle, said circles being substantially co-axial and lying in planes at right angles to the straight portion of the rod, said planes intersecting said straight portion at points within and adjacent the ends thereof, the inside diameter of the circle into which said end portions are looped being only slightly greater than the diameter of the rod.
40. A member for an articulated shelf, said member comprising a rod of substantially uniform diameter, said rod having a straight central portion and two end portions each bent through an angle greater than 90° with the straight portion and then looped into a circle, said circles being substantially co-axial and lying in planes at right angles to the straight portion of the rod, said planes intersecting said straight portion at points within and adjacent the ends thereof, the inside diameter of the circle into which said end portions are looped being only slightly greater than the diameter of the rod.
45. A member for an articulated shelf, said member comprising a rod of substantially uniform diameter, said rod having a straight central portion and two end portions each bent through an angle greater than 90° with the straight portion and then looped into a circle, said circles being substantially co-axial and lying in planes at right angles to the straight portion of the rod, said planes intersecting said straight portion at points within and adjacent the ends thereof, the inside diameter of the circle into which said end portions are looped being only slightly greater than the diameter of the rod.

CHARLES H. MACFARLAND.
